Alfred Rix

UNITED STATES PATENT OFFICE.

ALFRED RIX, OF SAN FRANCISCO, CALIFORNIA.

BALL-CASTER.

SPECIFICATION forming part of Letters Patent No. 372,387, dated November 1, 1887.

Application filed November 30, 1886. Serial No. 220,312. (Model.)

To all whom it may concern:

Be it known that I, ALFRED RIX, of the city and county of San Francisco and State of California, have made an Improvement in 5 Ball-Casters, of which the following is a specification.

The object of the invention is a caster having its point of support upon the floor directly beneath the leg supported, and at the 10 same time movable in any direction with no hitch and but little friction.

It consists of a ball within a socket considerably larger than the ball, with the space between filled not quite full of small balls, like 15 shot, which I call "pellets," loosely disposed in a single layer or bed, and acting as rollers, and kept in place by a stop at the lower edge of the socket.

The accompanying drawing is an enlarged 20 vertical central section view, (substantially,) and constitutes a part hereof.

A is the ball; B, the upper part of the socket; C, the lower part; D, the pellets; E, the stop, and E' a modification of the same. 25 This stop is placed high enough to clear the floor and low enough to allow a return-channel for the pellets not under pressure. The drawing shows a good example. The stop is so made and placed that the point at which 30 the pellets come in contact with it shall be near enough to the ball to prevent the pellets from wedging between the stop and the ball. The drawing shows two kinds—each properly constructed—so as to allow the pellets to rest and 35 move upon it without wedging, the one at E having its upper face a trough with a curve a little greater than that of the pellets, and the one at E' with its face plain and in line with the center of the ball.

40 As to the absolute size of the pellets, they should not be so small as to drop out on little wear, and as to their size relatively to the ball they should not be so large as to clog in the return-channel or prevent the ball from protruding sufficiently.

45 Pellets one-eighth of an inch in diameter work well with a ball one inch and a quarter in diameter. The fit of the pellets between the ball and socket should not be tight nor 50 very loose, but fairly free, so that when the

upper part of the socket rests upon the pellets the lower part of the socket will fall away from the ball slightly. The action will not prove satisfactory if the pellet-chamber is full. The amount of vacancy for the best action is 55 about one-tenth of the chamber. A few tests for any particular construction will determine how much the vacancy should be. This vacancy, when the caster is in action, is more or less distributed among the pellets under pressure, whereby their rubbing against each other is almost wholly prevented. The socket is shown divided at the center, with the lower part spun upon the upper. This allows the 60 upper part to be conveniently formed and finished, and the lower part to be made together with the stop; but the socket can be a single piece and the stop spun or otherwise fastened to it.

A convenient way of filling the pellet-chamber when the socket is divided at the center, as shown, is to turn the upper part of the socket upside down and arrange a few pellets in a single layer at the (then) bottom with the ball upon them. Then place over 75 them a form precisely like the lower part of the socket with the stop omitted. Finally, fill and remove the form and put on the lower part of the socket.

The operation is obvious. All the pellets 80 not under pressure between the upper hemispheres go to the lower part of the chamber, where they rest upon the stop and are free to be moved. As the caster moves forward in any direction the rear pellets roll on the 85 ball upward, over, and downward in front and drive the loose ones backward through the lower part of the chamber—the return-channel—a part turning to the right and a part to the left. This backward movement is also 90 aided by the action of the ball. As the ball always presses to the rear, it does not rub against the pellets resting on the stop in front, and as the pellets under pressure run substantially clear of each other the action is almost 95 wholly the rolling one.

Having thus described my invention, what I claim as new, and desire to secure by Letters Patent, is—

In and constituting a ball-caster, the com- 100

bination of the following parts, to wit: the ball A, the socket B, being enough more than a hemisphere to afford the return channel described, the stop E, presenting its upper side 5 to the pellets, as described, so as to avoid wedging, and the chamber formed by the ball, socket, and stop not quite filled with pellets

D, each part constructed and all united in the manner and for the purposes substantially as set forth.

ALFRED RIX.
